TYPOGRAPHICAL CASTING MACHINE

Richard R. Mead, Queens Village, N. Y., assignor
to Mergenthaler Linotype Company, a corpo-
ration of New York

Application June 22, 1936, Serial No. 86,590

20 Claims. (Cl. 199—49)

This invention relates to typographical casting machines, such as linotype machines of the general organization represented in United States patent to O. Mergenthaler No. 436,532, wherein 5 circulating matrices are released from a magazine in the order in which their characters are to appear in print, and then composed in line in an assembler, the composed line transferred from the assembler through an intermediate or delivery 10 channel into a vertically movable transporter or first elevator which presents the line to the face of a slotted mold, the mold filled with molten metal to form a slug against the matrices which produce the type characters thereon, and the 15 matrices thereafter returned through distributing mechanism to the magazine from which they started.

In the commercial machines, the matrices are of standard form and dimensions and are com- 20 monly provided in their casting edges with two superposed characters ranging in size from 5 pt. to a maximum of 14 pt. The letter characters on the individual matrices are usually alike, the upper one being roman and the lower one italic, 25 and the matrices are composed at one or the other of two different levels to bring either the roman or the italic characters into casting position. After composition, the matrices are main- 30 tained at their respective levels by means of rails which support them by their projecting ears dur- 35 ing their circulation through the machine from the time of composition until after the casting operation. In the assembler, the matrices are supported by their lower projecting ears on up- 40 per and lower rails, but in the intermediate channel during the line transfer and when the line is in the first elevator, those matrices stand- 45 ing at the lower level are sustained by their upper projecting ears on a pair of fixed upper rails, while those standing at the upper level are supported 50 by their lower projecting ears on a lower single rail. The lower rail in the first elevator is retractable and, after the casting operation and upon the ascent of the first elevator to the upper 55 transfer position, the retractable rail is moved forwardly from beneath the matrices standing at the upper level, in order to permit them to drop to the lower level preparatory to the trans- 60 fer of the line onto the second elevator bar. The retractable rail is controlled by cam surfaces formed on a fixed overhead bracket, which con- 65 stitutes part of the machine framework and just clears the top of the first elevator when the latter has been arrested at its upper transfer level.

55 In recent years, there has been an increasing

demand for larger faces and, in attempting to meet this demand, insofar as two-letter matrices are concerned, many serious difficulties have presented themselves. Thus, the distance between the top of the lower character to the top of the 5 upper character (characters inverted) of a standard two-letter matrix is the same throughout the various fonts and, in order to increase this distance for characters above 14 pt., without disturbing the location of the upper character so 10 that the latter character may still register as usual with the mold slot, it is necessary to utilize part of the regular space between the lower projecting ear and the top of the lower character. Consequently, when these two-letter matrices 15 are formed with characters above 14 pt., they must be supported in the first elevator at a correspondingly higher level to bring their lower characters into registration with the mold slot. Ordinarily, the space between the lower project- 20 ing ear and the routing notch for the lower character is seven-thirty-seconds of an inch, and it has been found that this space may be reduced to three-thirty-seconds of an inch, thereby giving four-thirty-seconds of an inch additional 25 character space. This means that when such additional character space is fully utilized, the matrices (which will hereafter be referred to as "special" matrices) will have to be supported in the first elevator at four-thirty-seconds of an 30 inch above the normal upper level.

In order to permit the "special" matrices to be thus supported, the present improvements pro- 35 vide, in addition to the customary auxiliary rail, which supports the regular matrices at the up- 40 per level, a supplementary auxiliary rail arranged immediately above the auxiliary rail and which supports the special matrices at the upper level in like manner. In the normal position of the parts, this rail stands retracted, so that the regu- 45 lar matrices which have previously been com- 50 posed in the assembler at the upper level, can be delivered onto the auxiliary rail in the usual way. When it is desired to use the machine with the special matrices, however, and to position these latter at the upper level, the supplementary aux- 55 iliary rail is adjusted rearwardly to an active position, wherein it overlies the usual auxiliary rail and, when thus positioned, it will support the special matrices in the transporter at the upper 60 level, with the lower edge of the lower routing notch in register with the datum line of the mold, which is the same for the special matrices as for the regular matrices.

After the casting operation, the transporter 55

is raised to the upper transfer position, wherein the composed line of matrices is transferred to the second elevator for distribution in the usual way. Before the matrices can be transferred to the second elevator however, they must be dropped to the lower level, and this is effected in the case of the regular matrices, as previously stated, by retracting the auxiliary rail. As to the special matrices, these are dropped to the lower level by the retraction of the supplementary auxiliary rail, which is brought about, in the present instance, by the forward movement of the auxiliary rail operating in the usual way.

When it is desired to cast from the lower characters on the special matrices, they are, like the regular matrices, assembled on the upper rail in the assembler and transferred through the delivery channel on the lower rail provided therein. In order that they may be delivered onto the supplementary auxiliary rail in the line transporter, however, the lower rail with which the delivery channel is provided is pivotally mounted at its right end adjacent the assembler elevator, so that it may at its left end be adjusted from its normal position in registry with the auxiliary rail to a higher position in registry with the supplementary auxiliary rail. When thus adjusted, it is plain that the special matrices will be properly delivered to the transporter.

Means are provided on the first elevator for adjusting the supplementary auxiliary rail to active position when desired and simultaneously therewith to locate the adjustable rail in the line delivery channel in registry with the supplementary auxiliary rail, so that actually the operator need concern himself with but one adjustment.

In one embodiment of the invention, the pivoted rail in the line delivery channel registers with the supplementary auxiliary rail in the line transporter only when the latter is in its active position and when the line transporter is at its normal or line receiving level. In another embodiment of the invention, means are provided for maintaining the rail in the line delivery channel in registering relation to the supplementary auxiliary rail in the line transporter at all times that the supplementary auxiliary rail is active.

As another feature of the invention, the line transporter is provided with a supplementary detent to cooperate with the special matrices when they are last in the line and are assembled at the upper level.

As still another feature, the line transporter is provided with a fixed rail formed with a depending tongue adapted to engage in notches formed in the upper faces of the lower projecting ears of the special matrices when the latter are assembled at the upper level, in order to prevent such matrices from being displaced from the transporter during the receding action of the mold after the casting operation.

The special matrices X (see Fig. 11) are similar to the regular matrices in most respects, that is, they are of standard form and dimensions and provided with an upper pair of projecting ears X¹ and a lower pair of projecting ears X². In 50 their casting edges, the matrices X are formed with two superposed characters X³ and X⁴, but these special matrices differ from the regular matrices in that the characters range in size throughout the various matrix fonts from 14 pt. 55 up to, say, 18 pt. instead of from 5 pt. to 14 pt., as in the case of the regular matrices. In addition, the lower projecting ears of the special matrices on their rear or non-casting edges are formed in 60 their upper surfaces with notches X⁵ for a purpose to be hereinafter described.

In the normal operation of the machine, the composed line of matrices is transferred, as usual, to the vertically movable first elevator or transporter A, wherein the matrices composed at the lower level (Fig. 4), whether they be regular or special matrices, will be supported by their upper projecting ears on a pair of fixed horizontal rails a, and those composed at the upper level will be supported by their lower projecting ears on an auxiliary retractable rail B (Fig. 2), if they be the regular matrices, or on a supplementary auxiliary rail B¹ located immediately above and supported by the auxiliary rail, if they be the special matrices (Fig. 3). Upon receipt of the 75

line, the first elevator descends until it banks upon a vise frame C, and in this way positions the line in front of a mold D between a pair of line clamping jaws (not shown) which are slidably mounted in guideways formed in the 5 vise frame.

The mold (Fig. 3) comprises as usual a body portion D¹, a cap portion D², and a pair of intermediate liners (not shown), the cap and body portions forming the upper and lower side walls of the mold slot, and the two liners the end walls thereof. The body portion of the mold also presents a pair of upper and lower alining ribs d and d¹, respectively, which are positioned 10 directly over and in engaging relation with the lower projecting ears of the matrices when the mold carrier is advanced to force the mold against the matrix line for the casting of the slug. In this connection, it may be mentioned that, due to the higher level at which the special matrices 15 must be supported in the first elevator to bring their lower characters into casting position, the upper alining rib d on the mold (which is intended only for the special matrices) is made proportionately thinner than the corresponding 20 rib on the regular mold used for the regular matrices.

After the casting operation and the mold D recedes, the first elevator A is raised to the "upper 25 transfer" position (Fig. 4) where the matrices are caused to assume a common level and the line is then shifted horizontally by a transfer slide onto the second elevator bar (likewise not shown) which carries the line upwardly to the distributing 30 mechanism.

As best shown in Figs. 1 and 2, the first elevator A includes a long vertical body portion, which is slidably mounted in the vise frame C, and the improved head portion which comprises 35 as usual, front and rear side walls A¹ and A² and the intermediate connecting block A³ (Figs. 2 and 3) arranged at one end of the elevator head. One of the fixed rails a is formed integral with the rear side wall A², while the other is 40 presented at the upper edge of a bar A⁴ extending longitudinally of the head portion and screwed to the front side wall A¹ of the elevator head. The bar A⁴ in its lower edge is recessed as at a¹, and the upper face of the recess presents a 45 depending tongue or lip a² that extends into the notches X⁵ formed in the lower ears of the special matrices when the latter are assembled at the upper level (see Fig. 3). The engagement of the tongue a² in the notches of the matrices 50 prevents the latter from being displaced from their proper positions in the elevator head upon the recession of the mold after a casting operation.

When the regular matrices (see Fig. 2) are 55 assembled at the upper level, they are supported on the auxiliary retractable rail B supported on a ledge A⁵ positioned beneath the front wall A¹ of the head portion and held in spaced relation therewith by depending portions A⁶ formed on said front wall (see Fig. 7). The auxiliary rail B is recessed at its opposite ends as at b, in order to cooperate with a pair of small levers A⁷ pivotally mounted adjacent their centers in the front wall A¹ of the head portion. These 60 levers at their lower ends are formed with nose portions a³ that engage in the recesses b just alluded to, and are urged in a direction (counter-clockwise) to maintain the auxiliary rail in its active position by a pair of springs A⁸ arranged 65 one at each side of the first elevator and having 70 75

an anchorage at their front ends in said elevator. The springs are connected at their rear extremities in eyes a⁴ with which the levers A⁷ are respectively provided. As just stated, the auxiliary rail B is normally held in its active position and, when the regular matrices are supported at the lower level by the engagement of their upper ears with the fixed rails a, the lower ears of said matrices stand beneath the auxiliary rail, whereas, when the regular matrices are at the upper 10 level, they are supported on the auxiliary rail by the engagement of their front lower ears on that portion of the auxiliary rail that projects beyond the rear face of the front side wall A¹ (see Fig. 2). 15

Before the regular matrices, which are supported at the upper level, can be transferred to the second elevator for distribution, they must, as previously stated, be dropped to the lower level in the transporter, and this is brought about by 20 the retraction of the auxiliary rail B, which is effected when the transporter arrives at its upper transfer level. For this purpose, the levers A⁷ are formed at their upper ends with cam surfaces a⁵ that engage bearing pieces E fixed in the 25 bracket E¹ that overlies the first elevator and which constitutes part of the machine frame. As the levers engage the members E, they are cammed in a direction (clockwise) to retract the auxiliary rail B against the tension of the springs 30 A⁸, whereupon the matrices will drop to the lower level as shown in Fig. 4. As the line transporter A descends to its normal position, the levers A⁷ are released by the bearing pieces E, whereupon the spring-actuated auxiliary rail is allowed 35 to return to its normal active position.

The supplementary auxiliary rail B¹, which supports the special matrices at the upper level, is formed in its bottom surface with a recess B² that fits over a raised portion B³ of the auxiliary 40 rail, but the recess B² is somewhat wider than said raised portion so as to allow for a certain amount of relative movement between the two rails for a purpose hereinafter set forth. Unlike the auxiliary rail, the supplementary auxiliary rail is normally maintained in a forward or retracted position (Fig. 2) in order to stand out of the way of the regular matrices when the latter are supported at the upper level on the auxiliary rail, but when the special matrices are used, the 45 supplementary auxiliary rail is moved rearwardly to the position shown in Fig. 3, wherein a supporting ledge is presented for the support of the special matrices at the upper level by means of their lower projecting ears X². The 50 difference in width between the recess B² in the bottom of the supplementary auxiliary rail and the raised portion B³ of the auxiliary rail is such that the supplementary auxiliary rail can be 55 adjusted from its inactive to its active position 60 without altering the position of the auxiliary rail.

The supplementary auxiliary rail B¹ is adjusted from its inactive to its active position by a pair of slide members F¹ and F² arranged at the top of the first elevator A and which are settable as a 65 unit. The upper slide member F¹ (see Figs. 3, 5 and 6) is tongued and grooved into a pair of spaced parallel retaining members G and G¹ screwed to the first elevator at the top and is formed in its bottom face and near the front with a recess F² 70 into which there projects a raised portion F³ formed on the bottom slide. The slides are each formed at their forward ends with upwardly projecting fingers F⁴ and F⁵, one fitting within the other, so as to facilitate the adjustment of the 75

slides as a unit. The normal position of the slides, i. e., the position corresponding to the retracted position of the supplementary auxiliary rail B^1 , is illustrated in Figs. 2 and 5, and this is determined by the banking of a lug F^6 formed on the top slide against an adjustable stop G^2 formed in a cross piece G^3 screwed to the slide retaining members G and G^1 . The rearward position of the slides, i. e., the position corresponding to the rearward or active position of the supplementary auxiliary rail, is determined by the banking of the lug F^6 against a second adjustable stop G^4 likewise threaded into a cross member G^5 similar to the cross member G^3 , but spaced somewhat to the rear thereof. The lower slide F^1 is held in either of its positions of adjustment by a spring-pressed detent G^6 that engages in one or another of a pair of recesses g and g^1 formed in the bottom surface of said lower slide, the detent being housed in a hole drilled in the first elevator for the purpose. Not only does the detent G^6 hold the lower slide F^1 in its different positions of adjustment, but actually it also holds the upper slide F , when both slides are in the forward or normal position, it being noted that under such conditions, the recess g^1 in the lower slide registers with a recess g^2 in the upper slide, and as the recess g^1 is large and extends through the lower slide, the detent G^6 will be enabled to cooperate with the recess g^2 to hold the upper slide in place. In order further to insure the simultaneous adjustment of the slides F and F^1 , the slide F is equipped with a pin f , having a head portion f^1 projecting into an elongated slot f^2 , and which will engage the bottom slide F^1 at the rear end of the slot to move it rearwardly along with the top slide, in the event the operator grasps only the latter in making the adjustment.

When the slides F and F^1 are adjusted from the position shown in Fig. 2 to that shown in Fig. 3, the setting of the supplementary auxiliary rail B^1 to active position will be effected through mechanism which includes a pair of rocker arms H pinned at the opposite ends of a rock shaft H^1 journaled in the overhanging portion of the elevator A and which are formed at their upper ends with bifurcated portions H^2 that straddle the flattened ends of a transverse rod H^3 journaled at its center in a bearing formed at the rear end of the top slide F . The rocker arms H are connected at their lower ends by means of socket joints to the forward ends of a pair of connecting rods H^4 , which in turn are connected at their rear ends by similar joints to a pair of levers H^5 arranged adjacent to and pivotally mounted on the same pivot rods as the levers A^7 which effect the retraction of the regular auxiliary rail B . These levers H^5 in turn are formed at their lower ends with nose portions h that engage in recesses b^2 formed in the top of the supplementary auxiliary rail B^1 , and it may be noted here that the supplementary auxiliary rail is slotted in the vicinity of the levers A^7 , in order that the latter may pass through the rail and cooperate with the regular auxiliary rail in the manner hereinbefore set forth.

According to the foregoing arrangement, the adjustment of the slides F and F^1 rearwardly (see Fig. 3) will effect a forward movement of the links H^4 , which in turn will actuate the levers H^5 in a direction (counterclockwise) to move the supplementary auxiliary rail B^1 rearwardly or into its active position, wherein it will support the special matrices X at the upper level.

75 As in the case of the regular matrices, the

special matrices, which have been supported at the upper level, must also be dropped to the lower level after the casting operation to permit transfer of such matrices to the second elevator for distribution, and this is effected by the retraction of the supplementary auxiliary rail. The supplementary auxiliary rail is retracted by the same means which effect the retraction of the regular auxiliary rail. As a matter of fact, when the supplementary auxiliary rail is in its active position (see Fig. 3), the raised portion B^3 of the auxiliary rail banks against the front face of the recess B^2 in the bottom of the supplementary auxiliary rail, so that, as the levers A^7 are cammed rearwardly upon the arrival of the line transporter at its upper transfer level, the supplementary rail B^1 will be moved forwardly or retracted along with the regular auxiliary rail B . The retraction of the supplementary rail turns the levers H^5 in a clockwise direction against the force exerted by compression springs H^6 associated one with each of said levers, and which seat in recesses formed in the front elevator wall A and bank against lateral extensions H^7 formed at the upper ends of the levers H^5 . This movement of the levers H^5 is permitted by reason of the fact that the top slide F , under such conditions, is allowed to move forwardly with respect to the bottom slide F^1 (see Fig. 4), the slot f^2 being long enough to permit this movement. Upon the descent of the elevator A from its upper line transfer position, the springs H^6 will act upon the levers H^5 to turn them in a counterclockwise direction again to locate the supplementary auxiliary slide B^1 in its active position to receive the next line of special matrices, the top slide F at the same time, through its connections with the levers H^5 being returned to its original or rearward setting. It might be noted here that when the slides F and F^1 are in their normal or outermost positions of adjustment corresponding to the retracted or inactive position of the supplementary auxiliary rail B^1 , the springs H^6 will be under compression, but they will not act to destroy the adjustment of the top slide, since, as previously stated, the detent G^6 holds the top slide when both slides are located in normal position. The force exerted by the springs H^6 is not sufficient to overcome the restraining effect of the detent.

The matrices are assembled in line in an assembler elevator I , where they are composed on one or another of a pair of rails, depending upon whether they are to be transferred to the line transporter A at the upper or lower level. From the assembler elevator, they pass through the line delivery channel J ; and here again, if the matrices are composed at the lower level, they will be supported in the delivery channel on fixed rails J^1 (Figs. 7 and 8) by their upper ears, whereas if they are composed at the upper level, they are supported by their lower ears on a grooved rail J^2 with which the delivery channel is provided. This is true both for the special matrices, as well as for the regular matrices. In accordance with the present invention however, this grooved rail J^2 is pivotally mounted at its right end (the entrance end of the delivery channel) on a pin J^3 mounted in the delivery channel and adjustably secured in place by a pair of nuts J^4 threaded on said pin at its outer end (see Fig. 5). According to the arrangement, the rail J^2 may be adjusted so as to locate its left end, i. e., where the matrices pass from the delivery channel to the line transporter, into register either with the auxiliary rail B or the supple-

mentary auxiliary rail B^1 , so that, depending upon whether the regular or special matrices are in use, they will be transferred to the auxiliary rail or the supplementary auxiliary rail, respectively.

5 The movable rail J^2 being grooved, the lower wall of the groove will present a bearing surface for the matrices as they pass through the delivery channel, the upper wall acting merely as a guide to insure the proper entry of the matrices into 10 the line transporter.

10 The pivoted rail J^2 is supported at its left end (see Figs. 7, 8, 9, and 10) by an angular shaped lever J^5 , the vertical arm of which is pivotally secured at its upper end to a fixed portion of the 15 delivery channel as at J^6 , and the horizontal arm of which is connected to the rail by a pin and slot connection J^7 . When the angular shaped lever J^5 hangs freely, the rail J^2 , under the influence of gravity, will assume a horizontal 20 position (Fig. 8) in register with the auxiliary rail B in the line transporter. However, when the angular shaped lever J^5 is swung to the right (see Fig. 7), the rail J^2 will be swung upwardly and located in a position in register with the 25 supplementary auxiliary rail B^1 (Fig. 7).

30 The swinging of the lever J^5 , and consequently the pivotal movement of the rail J^2 is effected automatically, and for this purpose the lever J^5 is formed on its left edge with a protrusion J^8 adapted to cooperate with the supplementary auxiliary rail B^1 . When the latter rail is in its 35 retracted position (Fig. 9), a recess b^3 formed in the right end thereof will be in alignment with the protrusion J^8 on the lever J^5 , and the depth of this recess is such that the lever is free to 40 assume its normal position wherein the rail J^2 will register with the auxiliary rail B . However, when the supplementary auxiliary rail B^1 is adjusted to its active position in the manner hereinbefore set forth, a bevelled portion b^4 on the rail B^1 , located at the front end of said recess b^3 , will cooperate with the protrusion J^8 on the 45 lever (Fig. 10), camming the latter to the right, and consequently effecting the upward movement of the rail J^2 to bring it into register with the supplementary auxiliary rail B^1 .

50 The protrusion J^8 is formed with inclined upper and lower faces, as well as rounded-off front and rear faces, the upper and lower inclined faces allowing the first elevator A to move between its upper transfer and its lower casting levels without interference when the supplementary auxiliary rail is in its active position, and the front and rear rounded-off faces permitting the vise frame (which, as is well known is pivotally mounted) to be swung downwardly and returned to normal 55 position. To facilitate this movement of the vise frame, the supplementary rail B^1 is provided at its right end and in its rear edge with a shoe b^5 bevelled in its front and rear faces, the front face acting to cam the lever J^5 out of the way when the vise frame is swung downwardly, and the rear bevelled face acting upon the lever in like manner when the vise frame is restored to 60 normal position.

65 At the entrance end of the first elevator jaw, there is provided, as usual, a small spring pawl K (Fig. 8) that is sprung outwardly by the incoming line of matrices to allow the line to pass through and which springs back again into position after the line has entered the transporter, to prevent the last matrices from falling out during the movements of the first elevator. In the 70 improved machine, an additional spring pawl K^1

is provided, located just above the regular pawl K and which cooperates with the special matrices X in like manner when they are positioned at the upper level.

75 It will be understood, of course, that a composed line may consist of special matrices assembled at the upper level, as well as special matrices assembled at the lower level, just as in the case of the regular matrices.

10 In Figs. 12 to 18, there is illustrated another embodiment of the invention, wherein the rail J^2 in the intermediate delivery channel is maintained in its set position, irrespective of the position of the first elevator. The devices for adjusting the supplementary auxiliary rail B^1 from active to inactive position in this embodiment are the same in all respects as those in the embodiment hereinbefore described. The difference lies in the mechanism for adjusting the pivoted rail J^2 .

15 According to this embodiment of the invention, the rail J^2 is adjusted from its lower position (Figs. 12, 13 and 16), wherein it registers with the auxiliary rail B into its upper position, wherein it registers with the supplementary auxiliary rail B^1 (Figs. 14, 15 and 17), through the medium of a bell crank lever L which includes a vertical arm L^1 pinned at the outer end of a short stub shaft L^2 journaled in the front wall of the delivery channel and a horizontal arm L^3 fixed at the rear end of said shaft and which is mounted in a recess J^9 with which said front wall is equipped. The horizontal arm L^3 is formed at its left end with a bifurcated portion l that straddles a pin J^{10} provided on rail J^2 , the arrangement being such that, as the bell crank lever L is moved in a clockwise direction, it will adjust the rail J^2 from its lower position shown in Fig. 16, to its upper position shown in Fig. 17; whereas, when it is moved in the opposite direction, the reverse positioning of the rail takes place.

20 The bell crank lever L is moved into its different positions of adjustment by a horizontal slide M tongued and grooved in the front wall of the delivery channel and which is formed with an elongated slot M^1 25 into which there projects a pin L^4 provided at the upper end of the vertical arm L^1 of said bell crank lever. When the slide M is moved from its normal position (Fig. 12) to the right (Fig. 14), it will 30 through the medium of a spring M^2 , fastened to the bell crank lever L and anchored in said slide, swing the bell crank lever to the right until it is arrested by the banking of the pivoted rail J^2 against an overlying stop J^{11} fixed in the delivery 35 channel front wall, in which position of the parts 40 the rail will register with the supplementary auxiliary rail B^1 . As the slide M is thus adjusted to the right, it releases a spring-pressed detent M^3 housed in the delivery channel wall, allowing it to 45 move forwardly into the path of a boss L^5 formed on the rear face of the lever arm L^1 , thus holding the lever L against turning to the left and disturbing the setting of the rail J^2 . Normally, the 50 detent M^3 is held in its retracted position out of the path of the boss L^5 by the slide M , the rear 55 face of which engages a pin m rising from the detent at the top, but when the slide is moved to the right, a recess m^1 formed therein is brought 60 into register with the pin, thus allowing a limited forward movement of the detent M^3 for the purpose just mentioned.

55 When the bell crank lever L is brought to rest by the banking of the rail J^2 against the stop J^{11} , there is an overthrow movement of the slide M , which is allowed by virtue of the slotted connec- 65 70 75

tion M^1 between the slide and lever, and this overthrow or excess movement is utilized during the return movement of the slide to the left to effect the retraction of the detent M^3 to release the bell crank lever. As shown in Fig. 14, the recess m^1 which receives the pin m on the detent is formed with a wedge surface, so that, as the slide M is moved toward the left, the pin will be forced inwardly and thus effect the retraction of the detent. Thereafter, the slide at the right end of the slot M^1 will contact with the pin L^4 in the bell crank lever and its further movement will rotate the bell crank L to the left, thereby returning the rail J^2 to its lower or normal position, which position incidentally is determined by an underlying stop J^{12} similar to the stop J^{11} . At this point, it may be stated that both of the stops J^{11} and J^{12} , as well as the boss L^5 on the bell crank lever, are in the form of eccentrics to give a limited range of adjustment so as accurately to locate the parts. It might also be mentioned that the slide M is held in its different positions of adjustment by a spring-pressed detent m^2 which engages in one or another of a pair of recesses m^3 (see Figs. 12 and 14) formed in the rear face of the slide.

The adjustment of the slide M is effected automatically with the setting of the supplementary auxiliary rail B^1 , and the mechanism for this purpose includes a slide member N carried by the first elevator head. The member N includes a shoe portion N^1 at the right tongued and grooved into the first elevator jaw (Figs. 12, 13 and 18) and formed in its rear edge with two spaced recesses N^2 and N^3 , one of which N^2 (that at the right) normally receives a forwardly projecting finger m^4 with which the slide M is provided, an intermediate portion N^4 connected to the shoe N^1 , and a plate N^5 connected to the intermediate portion N^4 and provided with an undercut slot N^6 which cooperates with a headed pin N^7 fixed in the elevator head at the bottom, the pin and slot connection serving to guide the member N in its adjusting movements. The slide member N is adjusted from the top adjusting slide F , and for this purpose it is connected with said slide by a horizontal arm N^8 formed at its opposite ends with bifurcated portions n and n^1 , one of which end portions n straddles a pin n^2 projecting downwardly from the slide F at its rear end, and the other of which end portions n^1 engages the flattened sides of a reduced portion n^3 at the upper end of a vertical shaft N^9 journaled in the elevator head. At the lower end of the shaft N^9 , there is pinned a fore-and-aft arm N^{10} , which is connected at its rear end to the plate N^5 .

According to the foregoing arrangement, the slide F will, when it is moved rearwardly to effect the adjustment of the supplementary auxiliary rail B^1 to active position, rotate the shaft N^9 in a clockwise direction, which in turn, through the connections just mentioned, will actuate the slide N to the right to effect the raising of the rail J^2 in the line delivery channel, all in the manner previously described. This adjustment, of course, must be effected when the first elevator is in the line receiving position, since only at this time is there any active cooperation between the slide M in the delivery channel and its actuating slide N in the first elevator. The adjustment of the rail J^2 is maintained until it is again adjusted to normal position by the outward manual adjustment of the slide F to effect the retraction of the supplementary slide B^1 . Here again, the adjustment can only take place when the first elevator is in

its line receiving position. It will be noted that the connection between the slides M and N is such that their cooperating portions can freely pass each other during the movement of the first elevator, without interference. Should the adjusting slide F be moved inwardly when the first elevator is in a position other than the line receiving position, or, say, when the vise frame is open, and the adjustment not corrected before the elevator is returned to its line receiving position, or the vise frame closed, the operation of the machine will not cause breakage of the parts, since, under such conditions, the second recess N^3 at the left in the slide element N will register with the protrusion m^4 on the slide M , and consequently, the parts will pass each other without interference.

In the accompanying drawings, the invention has been shown merely by way of example and in preferred form, and obviously, many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels to locate their lower characters in casting position, said means including a pair of relatively movable matrix supporting rails, and common automatically-actuated means carried by the transporter for retracting both said rails to allow the matrices to drop to the common lower level after a casting operation.

2. A typographical casting machine according to claim 1, wherein one rail is retracted by the reTRACTING movement of the other rail.

3. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels to locate their lower characters in casting position, said means including an auxiliary retractable rail for supporting the regular matrices at the upper level, a supplementary auxiliary retractable rail for supporting the special matrices at the upper level, means for setting the supplementary auxiliary retractable rail in active position, and automatic means acting through the auxiliary rail to move the supplementary auxiliary rail temporarily from active position after a casting operation to allow the matrices to drop to the common lower level.

4. A typographical casting machine adapted to be equipped with a set of regular two character matrices or a set of special two character matrices adapted to be presented to the mold at different casting levels when casting from the lower characters on the matrices and including, in combination, a line transporter provided with an auxiliary rail for supporting the regular matrices at one casting level, a supplementary auxiliary

5 rail for supporting the special matrices at another casting level, means for adjusting the supplementary auxiliary rail to active position, settable means mounted independently of the rails for delivering matrices to one or the other of said rails in the line transporter, and mechanism for automatically setting said means to effect the delivery of the matrices onto the supplementary auxiliary rail when said rail is adjusted to active position.

10 5. A typographical casting machine adapted to be equipped with a set of regular two character matrices or a set of special two character matrices adapted to be presented to the mold at different casting levels when casting from the lower characters on the matrices and including, in combination, a line transporter provided with an auxiliary rail for supporting the regular matrices at one casting level and a supplementary auxiliary rail for supporting the special matrices at another casting level, means for adjusting the supplementary auxiliary rail to active position, a line delivery channel provided with a movable rail adjustable to deliver matrices to one or the other of the rails in the line transporter, and automatic mechanism for effecting a proper corresponding adjustment of said channel rail when the supplementary auxiliary rail in the line transporter is adjusted to active position.

15 6. A typographical casting machine adapted to be equipped with a set of regular two character matrices or a set of special two character matrices adapted to be presented to the mold at different casting levels when casting from the lower characters on the matrices and including, in combination, a line transporter provided with an auxiliary rail for supporting the regular matrices at one casting level, a supplementary auxiliary rail for supporting the special matrices at another casting level, means for adjusting the supplementary auxiliary rail to active position, a line delivery channel provided with a movable rail adjustable to deliver matrices to one or the other of the rails in the line transporter, and mechanism controlled by the supplementary auxiliary rail in the line transporter for adjusting the channel rail to deliver matrices to one of said rails or the other depending upon the adjustment of said channel rail.

20 7. A typographical casting machine adapted to be equipped with a set of regular two character matrices or a set of special two character matrices adapted to be presented to the mold at different casting levels when casting from the lower characters on the matrices and including, in combination, a line transporter provided with an auxiliary rail for supporting the regular matrices at one casting level, a supplementary auxiliary rail for supporting the special matrices at another casting level, means for adjusting the supplementary auxiliary rail to active position, a line delivery channel provided with a rail pivotally mounted at the matrix receiving end and adjustable at the matrix delivery end into register with the auxiliary rail or the supplementary auxiliary rail in the line transporter, and devices under the control of the supplementary auxiliary rail adjusting means for effecting the proper adjustment of the rail in the line delivery channel.

25 8. A typographical casting machine adapted to be equipped with a set of regular two character matrices or a set of special two character matrices adapted to be presented to the mold at different casting levels when casting from the lower characters on the matrices and including, in combination, a line transporter provided with an aux-

iliary rail for supporting the regular matrices at one casting level, a supplementary auxiliary rail for supporting the special matrices at another casting level, means for adjusting the supplementary auxiliary rail to active position, a line delivery channel provided with an adjustable rail for delivering matrices to one or the other of the rails in the line transporter, and mechanism including a pivoted lever operable under the control of the supplementary auxiliary rail adjusting means for effecting the proper adjustment of the rail in the line delivery channel.

30 9. A typographical casting machine adapted to be equipped with a set of regular two character matrices or a set of special two character matrices adapted to be presented to the mold at different casting levels when casting from the lower characters on the matrices and including, in combination, a line transporter provided with an auxiliary rail for supporting the regular matrices at one casting level, a supplementary auxiliary rail for supporting the special matrices at another casting level, means for adjusting the supplementary auxiliary rail to active position, a line delivery channel provided with an adjustable rail for delivering matrices to one or the other of the rails in the line transporter, mechanism under the control of the supplementary auxiliary rail adjusting means for effecting the proper adjustment of the rail in the line delivery channel, and means for holding said rail in its adjusted position.

35 10. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels to locate their lower characters in casting position, a line delivery channel provided with an adjustable rail for delivering matrices to one level or the other in the line transporter, and mechanism including devices carried in part by the line transporter for effecting the proper adjustment of the rail in the delivery channel.

40 11. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels to locate their lower characters in casting position, a line delivery channel provided with an adjustable rail for delivering matrices to one level or the other in the line transporter, mechanism including devices carried by the line transporter and other devices carried by a fixed part of the machine for effecting the proper adjustment of the rail in the line delivery channel, the devices on the transporter and on the fixed part of the machine cooperating to permit the adjustment of the rail in the delivery channel when the line transporter is in line receiving position.

45 12. A typographical casting machine arranged to be equipped with a set of regular two character matrices or a set of special two character matrices adapted to be presented to the mold at different upper levels when casting from the lower characters on the matrices and including, in combina-

tion, a line transporter, means in the transporter for locating said sets of matrices at relatively different upper levels to locate their lower characters in casting position, a line delivery channel provided with an adjustable rail for delivering matrices to one level or the other in the line transporter, mechanism including devices carried by the line transporter and other devices carried by a fixed part of the machine for effecting the proper adjustment of the rail in the line delivery channel, and means for maintaining the adjusted positions of said channel rail irrespective of the position of the line transporter.

13. A typographical casting machine arranged to be equipped with matrices having projecting ears, a line transporter adapted to present a composed line of matrices to the mold, means in the line transporter for supporting a composed line of said matrices in casting position by means of their projecting ears, and a device in the line transporter equipped with an element adapted to engage in notches formed in the projecting ears of said matrices to hold the matrices against displacement in a direction toward the mold.

14. A matrix for a typographical casting machine adapted with others to be composed in line and supported in casting position in said machine, said matrix having upper and lower projecting ears on the rear or casting edge thereof, and similar projecting ears on the front or non-casting edge thereof, the lower projecting ear on the non-casting edge being provided with a notch adapted to cooperate with means in the line supporter whereby the matrix is held against displacement in a direction toward the mold.

15. A typographical casting machine arranged to be equipped with a set of regular two character matrices or a set of special two character matrices adapted to be presented to the mold at different upper levels when casting from the lower characters on the matrices and including, in combination, a line transporter, means including a pair of rails for supporting the regular and the special matrices at their different upper levels, and independent detents cooperating with the matrices at the different levels for holding them against inadvertent endwise movement in the transporter.

16. A typographical casting machine arranged to be equipped with a set of regular two character matrices or a set of special two character matrices adapted to be presented to the mold at different upper levels when casting from the lower characters on the matrices and including, in combination, a line transporter, means in the transporter for supporting the sets of matrices at their different levels including a normally active auxiliary rail and a normally inactive supplementary auxiliary rail, a line delivery channel provided with a movable rail normally set to deliver matrices to the auxiliary rail in the line transporter, and means including devices on the line transporter for simultaneously adjusting the supplementary auxiliary rail to active position and the movable rail in the delivery channel into a position to deliver matrices onto said supplementary auxiliary rail.

17. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels, to locate their lower char-

acters in casting position, said means including a pair of relatively movable supporting rails, one of said rails being normally in active position and the other in inactive position, and devices for adjusting the second rail to and from active position, said devices including a pair of vertical intermediately pivoted levers connected at their lower ends to the second rail adjacent its opposite ends, a pair of vertical rocker arms disposed forwardly of the two levers, a pair of fore-and-aft bars connecting the lower ends of the rocker arms to the upper ends of the levers, a transverse rod connecting the upper ends of the rocker arms to operate them in unison, and a manually operable slide connected to the transverse rod and extending forwardly therefrom.

18. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels, to locate their lower characters in casting position, said means including a pair of relatively movable supporting rails, one of said rails being normally in active position and the other in inactive position, and devices for adjusting the second rail to and from active position, said devices including a pair of vertical intermediately pivoted levers connected at their lower ends to the second rail adjacent its opposite ends, a pair of vertical rocker arms disposed forwardly of the two levers, a pair of fore-and-aft bars connecting the lower ends of the rocker arms to the upper ends of the levers, a transverse rod connecting the upper ends of the rocker arms to operate them in unison, a manually operable slide connected to the transverse rod and extending forwardly therefrom, and a pair of stops to limit the movement of the manually operable slide in opposite directions.

19. A typographical casting machine arranged to be equipped with a set of regular two character matrices or a set of special two character matrices adapted to be presented to the mold at different upper levels when casting from the lower characters on the matrices and including, in combination, a line transporter, means in the transporter for locating said sets of matrices at relatively different upper levels to locate their lower characters in casting position, said means including a pair of relatively movable supporting rails, one of said rails being normally in active position and the other in inactive position, and devices including slide means located at the top of the line transporter and adjustable inwardly to effect the adjustment of the second rail to active position and outwardly to effect the return of said rail to normal or inactive position, characterized by the fact that the slide means includes two relatively movable members, one movable with said second rail as the latter is retracted to allow the matrices to drop to the lower level for distribution, and means for retaining the other member in its different adjusted positions to maintain the position of adjustment of said rail.

20. A typographical casting machine arranged to be equipped with a set of regular two character matrices or a set of special two character matrices adapted to be presented to the mold at different upper levels when casting from the lower characters on the matrices and including, in combination, a line transporter, means in the

transporter for locating said sets of matrices at relatively different upper levels to locate their lower characters in casting position, said means including a pair of relatively movable supporting rails, one of said rails being normally in active position and the other in inactive position, and devices including slide means located at the top of the line transporter and adjustable inwardly to effect the adjustment of the second rail to active position and outwardly to effect the return of said rail to normal or inactive position, characterized by the fact that the slide means in-

cludes two relatively movable members, one movable with said second rail as the latter is retracted to allow the matrices to drop to the lower level for distribution, means for retaining the other member in its different adjusted positions to maintain the position of adjustment of said rail, and means for insuring the proper setting of one of said members when the other said member is adjusted to locate said second rail in active position. 5

RICHARD R. MEAD.
